A. C. FISCHER

SUPPORTING DEVICE FOR CONCRETE SEPARATING STRIPS

Filed April 2, 1926

Inventor:

Albert C. Fischer,

By Dean W. Smith

UNITED STATES PATENT OFFICE.

ALBERT C. FISCHER, OF CHICAGO, ILLINOIS.

SUPPORTING DEVICE FOR CONCRETE-SEPARATING STRIPS.

Application filed April 2, 1926. Serial No. 99,289.

My invention relates in general to the construction of roadways and the like concrete structures, and has particular reference to a so-called contraction joint as used primarily 5 as a separating strip for the concrete sections of a roadway.

The primary object of my invention is to provide a combination device which will support the separating strip to facilitate installation of the same, and also reinforce the strip in the roadway after the joint has been formed with the concrete poured around the same.

An illustrative embodiment of the invention is shown in the accompanying drawing, in which Figure 1 is a perspective view of a section of a separating strip; Figure 2 is a perspective view of the supporting device; Figure 3 is a perspective view of a separating strip installed prior to the pouring of the concrete sections and illustrating the application of the invention; Figure 4 is an end view of the supporting device and Figure 5 is a perspective view of a separating strip having an expansion crown carried thereby.

Referring now to the drawing in detail, 1— represents the separating strip, which in most instances I prefer to produce from sheet metal, constructing the same with a tongue 2— on one side and groove 3— on its opposite side. This tongue and groove structure will provide a projection on one side of the strip which will be imbedded in 30 one of the concrete sections with the concrete in the opposite section filling in the groove 3— on the opposite side of the strip. The purpose of this construction is to lock the two sections together and prevent 35 the same from riding up or buckling due to expansion.

In some cases the top layer of the road 40 will cover the top of the joint. However, when an expansion crown 4— (Figure 5) is used it will be exposed, but the same will 45 not be forced up due to the fact that the separating strip is anchored by the tongue and groove. This same feature also applies 50 in cases where a space is left on the top of the separating strip and a poured crown is used.

The crown 4— shown in Figure 5, is of 55 preformed structure and the material from which it is made will be fibrated asphalt or any other suitable compressible material. In the case of a poured crown the material

may be asphalt or any other material suitable for the purpose.

As shown in Figure 3, to install the strip it must be supported on the subsoil or foundation 5— of the roadway, and properly held in position until the concrete sections are poured. To support the strip I equip the same with a supporting device, which may be stamped or otherwise formed from sheet metal, and comprising an angular attaching plate 6—, which is made to conform to the angle of the tongue and groove of the strip, having holes or openings punched therein, corresponding to like holes 70 or openings in the separating strip, so that rivets or other suitable attaching means may be employed to attach the plate.

The web portion 7— which overlies the flat side of the strip below the tongue and groove is cut so as to provide a stake 8—, which is sunk in the subsoil or foundation 5— of the roadway, and with the material on opposite sides of this stake 8— turned up at right angles to the stake 8— to provide horizontal arms 9 and 10 to project from opposite sides of the device, and likewise from opposite sides of the strip. When the supporting device is attached thereto the arms 9 and 10 lie upon the surface of the subsoil or foundation 5— of the roadway, as best shown in Figure 3.

With this construction the stake 8— and the arms 9 and 10 properly support the separating strip prior to the pouring of the concrete sections and the arms 9 and 10 further act to prevent the strip from sinking into the subsoil or foundation 5— of the roadway, since they lie upon the subsoil or foundation 5— as explained.

Ordinarily the separating strips 1— will be made in short lengths, at least the length of the same will not extend all the way across the roadway. These sections may be very conveniently joined by utilizing the supporting device for this purpose. For instance, by punching or otherwise forming holes or openings 11 and 12 in the tongue and groove of the strip at both ends of the same, two or more sections of strip may be placed end to end, and by using the plate 6— to overlap the abutting sections rivets or other securing means may engage the openings or holes 11 and 12 and lock the sections together by the plate.

In Figure 4 is shown a slightly modified construction of a supporting device in that

instead of terminating the plate —6— at the bend —13—, I will form the same with an extension —14— which will overlie the flat side of the strip above the tongue and groove. 5 From the above it will readily be seen that by a very simple stamping, or it may possibly be a casting, but even regardless of how made, I can provide a very simple method of supporting these separating strips 10 so that they may be evenly imbedded in the concrete and prevented from sinking into the subsoil or foundation of the roadway.

I claim:

1. A support for strips of the class de- 15 scribed, comprising an oblong plate cut at one end to provide integral and separately acting parts, the intermediate one of the parts projecting downwardly as a staking means, the two outside parts being bent in 20 opposite directions and at right angles to

the staking means to provide transverse supports, the uncut part of the plate adapted to lie flush against a separating strip and means for attaching the same thereto.

2. A support for strips of the class de- 25 scribed, comprising an oblong plate cut at one end to provide integral and separately acting parts, the intermediate one of the parts projecting downwardly as a staking means, the two outside parts being bent in 30 opposite directions and at right angles to the staking means to provide transverse supports, the uncut part of the plate being shaped to conform to the side of a tongue and groove strip and means for attaching 35 the plate to the strip.

Signed at Chicago, Illinois, this 30th day of March 1926.

ALBERT C. FISCHER.
